BATHTUB PANEL OR SIMILAR ARTICLE

Hazel P. Rodman, 1315 S. Union Ave., Alliance, Ohio

Filed Feb. 16, 1960, Ser. No. 59,424

Term of patent 14 years

(Cl. D4—4)

FIG. 1

FIG. 2

FIG. 3

FIG. 5

FIG. 4

Fig. 1 is a front perspective of a bathtub panel embodying my new design, the broken line representation of a bathtub being for illustrative purposes only;

Fig. 2 is a front elevational view thereof;

Fig. 3 is an enlarged top plan view thereof, the right end being broken away for convenience of illustration;

Fig. 4 is a vertical cross-sectional view thereof taken on line 4—4 of FIG. 2; and

Fig. 5 is an enlarged horizontal cross-sectional view thereof taken on line 5—5 of FIG. 2.

I claim:

The ornamental design for a bathtub panel or similar article, substantially as shown and described.
